[57] CLAIM

The ornamental design for a pipeholder or the like,
substantially as shown and described.

DESCRIPTION

FIG. 1 is a front elevational view of a pipeholder or the like showing my new design;

FIG. 2 is a top plan view;

FIG. 3 is a side elevational view; and

FIG. 4 is a longitudinal sectional view taken along an imaginary horizontal line which would bisect FIG. 2.

Fig. 1.

Fig. 2.

Fig. 3.

Fig. 4.
